United States Patent Office

Des. 208,677

Patented Sept. 19, 1967

208,677

AIR CURTAIN

Herman M. Melzer, McKeesport, Pa.
(302 4th St., Charleroi, Pa. 15022)

Filed May 14, 1965, Ser. No. 85,284

Term of patent 7 years

(Cl. D62—4)

FIG. 2

FIG. 1

FIG. 1 is an isometric view of an air curtain showing my new design;

FIG. 2 is a top plan view thereof. The rear of the air curtain is plane and unornamented.

I claim:

The ornamental design for an air curtain, as shown and described.
